GUARD FOR DRINKING GLASSES

Randall E. Smith, Jackson Heights, N. Y.

Application September 21, 1938, Serial No. 230,925

2 Claims. (Cl. 65—13)

This invention relates to a guard for drinking glasses such as commonly employed for beverages, and has for its object the production of a guard adapted to be placed in the mouth of the glass to prevent ice or other solid substances from passing into the mouth of the drinker when the glass is in use.

Another object is to provide a guard for drinking glasses that can be used as an advertisement.

Another object is to provide a guard for drinking glasses made of paper, cardboard or the like, which is so cheap that it can be thrown away after each use.

A further object is to provide a guard for drinking glasses which snaps on the glass and is thereby retained in operative position without the necessity of the user holding the same in place.

The drawing illustrates a preferred embodiment of the invention. However, it is understood in adapting same to meet different conditions, various changes in the form, proportion and details of construction may be resorted to, without departing from the nature of the invention as claimed herein.

In connection with drinking iced drinks such as Coca Cola and the like, it is objectionable to have the ice contact the drinker's upper lip and teeth. This causes an unpleasant sensation and also interferes with the flow of liquid into the mouth. The present invention eliminates this and other difficulties while at the same time it affords a simple and cheap means of advertising, the guard being made of wax paper, cardboard or the like which costs so little that the guard can be thrown away and a separate guard used with each drink served.

This would be impossible with any guard assembled from a multiplicity of parts, such, for example, as a guard comprising a disk having a series of hooks attached thereto adapted to engage the upper edge of the glass; or a guard made from metal and having a downwardly extending tab or handle; or a sheet metal disk adapted to fit into the open neck of the glass to be held therein by friction.

Many guards for dispensing drinks have heretofore been attempted, mainly for use in connection with cocktails or the like, for the purpose of straining the liquid as it is poured from a glass or jigger into the drinking glass, and some of these guards have been used in the past to prevent floating material such as ice and fruit from coming in contact with the mouth, but the majority of such guards were so made that they must

be held in place and their construction was so expensive that they could not be thrown away after each drink.

In the accompanying drawing:

5 Figure 1 is a plan view of a guard embodying this invention;

Figure 2 is a view on the line 2—2, Figure 1, showing a glass in section and the guard in section thereon;

Figure 3 is a sectional view of another form of glass and guard;

Figure 4 is a plan view of a modified form of guard similar to that shown in Figure 1; and

10 Figure 5 is a sectional view of the guard, Figure 3, showing the formation of the rolled edge of the glass retaining portion of the guard, Figure 3, or the guard shown in any of the other figures.

The glass or tumblers 10 and 11, Figures 2 and 3 respectively, are types of glasses in common use 15 for dispensing Coca Cola and similar beverages. The glass 10 has a beaded lip as shown at 12, while the upper edge 13 of the glass 11 is rounded off in the usual manner. It will be understood that these glasses are shown merely by way of 20 illustration and that the new guard herein disclosed may be used with and shaped for use with a glass having any form of top, as such modifications as are necessary to change the guard to adapt it for use with a given glass are obvious.

25 The guard, generally denoted by the numeral 14, may be made of any suitable material such as paper, cardboard, thin sheet aluminum or any one of the numerous molded products, such as Bakelite, catalin or the like. The preferred form 30 where extreme cheapness is desired, as is necessary when the guard is used as an advertising device, is a form of heavy paper or cardboard similar to that used for milk bottle caps and tops. Such cardboard is readily formed into shape and 35 is treated with paraffin or the like to render it more or less moistureproof, and to stiffen it. For the purposes of this disclosure, it will be assumed that the guard is made from a heavy paper stock 40 suitably treated to make it sufficiently waterproof for the purpose intended, and to give the clamping edge of the guard sufficient springiness or 45 resiliency to hold the guard in position as hereinafter described.

50 The guard as just described is first blanked out and then formed in a suitable mold, the portion 15 of the guard being formed as shown, to embrace a portion of the upper rim of the glass. The center portion 16 of the guard is depressed so that it will lie slightly below the top edge of the

glass and extend completely across the same, except that a relatively narrow open space 17 is provided through which liquid may pass.

In order to provide additional passages for the liquid on the side of the glass which is placed against the user's mouth, additional openings may be supplied. These may take the form of some trade mark or slogan, such as "Sipmaster" as indicated at 18 or such as the openings indicated at 19 and 20, Figure 4.

If desired, one or more holes, such as that indicated at 21 may be punched through the center portion 16 of the guard to provide for the usual straw commonly used when drinking beverages. This hole is preferably located adjacent to the edge 15 of the guard so that liquid will not spill therethrough when the guard is tipped in the act of drinking.

The edge 15 is formed to extend over the edge of the glass as shown at 22 in the figures, is continued downward as shown at 23 and may be rolled up as shown at 24 in order to provide a stiff and resilient edge. As shown in Figure 5, the construction is such that the rolled-up portion 24 is sprung inwardly and lies against the lower portion 25 of the outwardly extending edge 15. This forms a gripping portion for the guard and in order to facilitate the ready attachment of the guard to the glass, one end of this gripping portion is flared downwardly as shown at 26. In this flare portion, the rolled-up portion 24 is open or separated from 25 so that the upper edge of the glass easily fits therebetween and by inserting the edge of the glass in this open portion and then giving the guard a twisting motion, the guard may be instantly attached to the glass, which it will firmly grip by reason of the resilient action of the gripping portion of the guard. This eliminates the necessity of holding the guard in position in the glass when using it and yet the guard may be instantly detached and thrown away after use.

If necessary, to give further strength and resiliency to the gripping portion of the guard, a wire or the like can be inserted at 26 in the rolled-up portion 24, thereby forming additional resilient means adapted to hold the guard in place.

It will be obvious from the foregoing that the invention comprises a one piece guard or strainer constituting an article of manufacture adapted to fit into a glass and be retained thereon while in use. The device may be regarded as a guard if imperforate, the space 17 permitting the liquid to flow out of the glass, and it may be regarded as a strainer when perforate, as shown at 18 and 20, in Figure 4, for it is obvious that the guard 10 could be made to fit into and completely close the glass, all of the liquid being withdrawn through the openings 19 and 20.

It is also obvious that the gripping edge 15 can be extended completely around the periphery of the guard, or that two such edges could be put at opposite points or at several points around the periphery of the guard. As such modifications are obvious, they are not illustrated nor described in detail.

What is claimed is:

1. A guard for glasses comprising a one piece member formed of non-metallic material and adapted to lie in the open end of said glass below the rim thereof, an opening in said guard through which liquid may be discharged from said glass, and a second opening spaced apart from said first opening for admitting air to said glass when liquid is passing through said first opening, said member having an annular edge adapted to extend over the rim of said glass and downwardly on the outside thereof, said annular edge being stiffened by folding and rolling the material along said edge back on itself.

2. A non-metallic one piece guard for glasses comprising a member adapted to lie within the mouth of a glass below the upper edge thereof to partially close the same leaving an opening between said member and glass, said guard having an aperture spaced apart from said opening and adapted to admit air to the glass independently of said opening, said member having an inwardly rolled formed edge adapted to engage and overlie the rim of the glass near the top thereof with said inwardly rolled edge on the outside thereof to support the guard.

RANDALL E. SMITH.
